CLAIM

The ornamental design for a tool for scratch tickets, as shown and described.

DESCRIPTION

FIG. 1 is an isometric view of a tool for scratch tickets; FIG. 2 is a rear view thereof;

FIG. 3 is a front view thereof;

FIG. 4 is a left side view thereof;

FIG. 5 is a right side view thereof;

FIG. 6 is a top view thereof;

FIG. 7 is a bottom view thereof; and,

FIG. 8 is an isometric view of a tool for scratch tickets with the portion comprising bristles extended.

The broken lines illustrate portions of the tool for scratch tickets that form no part of the claimed design.

1 Claim, 6 Drawing Sheets(56)
